SHOE POLISHER

Filed Feb. 8, 1937

FIG. 3.

FIG. 2.

INVENTOR:

THOMAS GUTTERSON

BY

Benedict Hale

ATTORNEY

UNITED STATES PATENT OFFICE

2,110,362

SHOE POLISHER

Thomas Gutterson, San Francisco, Calif.

Application February 8, 1937, Serial No. 124,696

6 Claims. (Cl. 15—266)

This invention relates to improvements in shoe polishers and more particularly to mechanical means for repolishing shoes.

Among the objects of the invention is to provide simple and convenient means for removing dust and light scratches from and restoring the luster to previously polished shoes.

Another object is to impart a mechanical movement to a polishing strip, simulating the movement of such a strip in the hands of a shoe shiner.

Another object is to provide for the easy removal and replacement of the polishing cloth.

Other objects and advantages will appear as the description progresses.

In this specification and the accompanying drawing the invention is disclosed in its preferred form. But it is to be understood that it is not limited to this form because it may be embodied in other forms without departing from the spirit of the invention as defined in the claims following the description.

In the one sheet of drawing:

Fig. 1 is a side elevation of a shoe repolisher constructed in accordance with this invention showing in dotted construction a shoe inserted into the polisher.

Fig. 2 is a plan view from below of the same.

Fig. 3 is a plan view of the polishing strip removed from the polisher.

In detail the construction illustrated in the drawing, referring first to Fig. 2 comprises the base plate 1 having its opposite ends bent down at 2 and 3 and flanged outwardly at 4 and 5, to elevate the plate above the floor level A.

The plate 1 tapers slightly from 3 to 2 and has the longitudinal ribs 6, 6 struck up above the upper plane thereof to stiffen the plate and to receive the traction of the shoe sole 7. One edge of the base plate 1 is bent down at 8 and flanged inwardly at 9. The opposite edge is similarly bent down at 10 and flanged inwardly at 12. This latter flange 12 lies in close proximity to the floor A, and is provided with a series of teeth 13, and the spring hole 14', see Fig. 2.

The polishing strap 14, see Fig. 3, consists preferably of a length of heavy drill woven cotton flannel having a heavy cotton pile on the inside. The length is preferably cut parallel with the warp to prevent stretching. The "drill" weave gives a certain bias flexibility across the length, causing the strip 14 to adjust itself to the shoe B. The ends 15 and 16 of the strip are cut oblique to the length, so that the strip is longer on the lateral edge 17 than the other edge 18. Both

the ends 15, 16 are suitably hemmed and the edge 15 has the bar 19 inserted therein to prevent longitudinal wrinkling.

The spring 20 has one end inserted through a hole in the bar 19 to attach it to the end of the strip 14. The other end of the spring engages the hole 14' in the flange 12. The free end 16 of the strip is then carried around the smoothly flanged edge 8 over the top of the plate 1, around the flanged edge 10 and over the serrate flange 12 and has its hemmed edge engaged by the teeth 13, 13. The oblique arrangement of the strip 14 with respect to the tapered base plate is best shown in Fig. 2.

This invention operates substantially as follows: The end flanges 4 and 5 are preferably screwed to the floor A or otherwise fixed to a firm foundation. The toe B of the shoe, while on the foot of the wearer, is thrust under the strip 14 from the edge 17. During this act the spring 20 expands to give the required length of strip 14 above the plate 1. Thus the longitudinal travel of the shoe along the plate 1 causes a transverse, slightly oblique travel of the strip across the shoe vamp. By repeating the operation of pushing the shoe in and out of the apparatus the strip 14 is drawn across the shoe, in addition to the in and out rubbing effect as the shoe moves back and forth beneath the strip. In this manner a new polish is restored to a dulled shine. After the strip 14 has been used once, the edge 17 will remain elevated to form a "tunnel" to receive the shoe toe B.

When the polishing cloth strip 14 becomes worn, the screws 22, 22 are removed and a new strip substituted. The serrate flange 12 lies close to the floor to prevent the hemmed end 16 from pulling past the teeth 13, 13.

The oblique pull of the spring 20, see Fig. 2, prevents the strip 14 from wrinkling when the shoe B is inserted thereunder.

Having thus described this invention, what is claimed and desired to secure by Letters Patent is:

1. A shoe polisher including a plate; a polishing strip wrapped around said plate and resiliently attached thereto. 45

2. A shoe polisher including a plate; a polishing strip wrapped obliquely around and resiliently attached to said plate. 50

3. A shoe polisher including a tapered plate; a polishing strip wrapped obliquely around said plate and resiliently secured to the under side thereof. 55

4. A shoe polisher including a plate; a polish-

ing strip wrapped around said plate and having one end fixed thereto; and a resilient connection between said plate and the free end of said strip.

5. A shoe polisher including a plate having inturned edges, one of said edges having teeth thereon; a strip having one edge attached to said teeth and wrapped around said plate and

resiliently attached to the underside of said plate.

6. A shoe polisher including a tapered plate; a strip wrapped obliquely around and resiliently secured beneath said plate and so arranged that it will move obliquely across a shoe moved longitudinally on said plate. 5

THOMAS GUTTERSON.
